CLAIM

The ornamental design for facing and insert portions of a fit-for-purpose sensor housing for a downhole tool, as shown and described.

DESCRIPTION

FIG. 1 is a front elevation view of the facing and insert portions of a fit-for-purpose sensor housing for a downhole tool showing my design;

FIG. 2 is a back elevation view thereof;

FIG. 3 is a side view thereof;

FIG. 4 is a top view thereof; and,

FIG. 5 is front and side perspective view thereof.

The fit-for-purpose sensor housing for a downhole sensor tool is a sensor housing to adjust the downhole tool for purpose of being deployed into a borehole of a particular diameter and measurement of particular conditions. The facing and insert portions are separated by a body portion with a variable thickness dimension. The broken line features are illustrative and form no part of the claimed design.
